UNITED STATES PATENT OFFICE

2,450,643

SHOE MACHINE

Anton E. Diessel, St. Louis, Mo., assignor to
 International Shoe Company, St. Louis, Mo., a
 corporation of Delaware

Application October 29, 1945, Serial No. 625,287

7 Claims. (Cl. 12—1)

1

This invention relates to shoe machines, and more particularly to a machine for forming and conditioning closed slip-last uppers.

In the manufacture of slip-last shoes of the closed toe and heel type, difficulty has been experienced in seating heel counters and box toe inserts. Particularly, in the construction of slip-last uppers, it has been difficult to avoid a pucker between the upper and the sock lining at the toe, to conform the toe portion to the last and to form a satisfactory margin of the shoe at the seam between the upper, the sock lining, and the platform cover.

The primary object of the present invention is to provide a machine whereby a slip-last upper, having the platform cover secured thereto, may be molded to a set form and a box toe seated in the toe section of the upper to give a finished appearance to the shoe.

Another object of the invention is to provide a machine of the class described, which may be conveniently operated even by unskilled shoe workers to form and condition slip-last uppers having the characteristics heretofore mentioned.

Additional structural and operative advantages of the machine of the invention will be recognized from the following detailed description, without further specific mention, reference being made to the accompanying drawings, in which:

Fig. 1 is a side elevation of the machine in normal operative position without the slip-last upper being mounted thereon;

Fig. 2 is a partial elevation of the left or front end of the machine, as illustrated in Fig. 1;

Fig. 3 is a view similar to Fig. 2, viewing the machine from the right or rear end, as illustrated in Fig. 1;

Fig. 4 is a vertical section taken substantially on the line 4—4 of Fig. 1;

Fig. 5 is a horizontal section taken substantially on the line 5—5 of Fig. 1;

Fig. 6 is a view similar to Fig. 1, but with the parts in adjustment in which the former elements are contracted;

Fig. 7 is an enlarged vertical section through the head of the machine with the parts in the position as illustrated in Fig. 6;

Fig. 8 is a view similar to Fig. 7, but with the parts in position for the reception of the slip-last upper, which is illustrated in this figure, before the forming members have been extended;

Fig. 9 is a partial section of the parts illustrated in Fig. 8 with the forming members in the position

as illustrated in Fig. 1, with the upper mounted on the machine;

Fig. 10 is a vertical section on the line 10—10 of Fig. 7;

Fig. 11 is a top plan view of the forming member for the fore part of the upper;

Fig. 12 is a partial end elevation of the upper section of the support bracket for the forming member;

Fig. 13 is an enlarged section of a portion of the toe of the slip-last upper after it has been formed, but before the platform cover has been turned over; and

Fig. 14 is a view similar to Fig. 13 showing the finished molding of the toe of the slip-last upper, and with the platform cover turned over.

In the embodiment of the invention selected for illustration, the machine includes a base plate 1 for attachment to a permanent horizontal support. A pedestal 2, integral with the base plate 1 and having the form of a hollow cylinder, extends upwardly therefrom.

Integral with the pedestal and at the top thereof is a head section 3 having an opening 4 therethrough defined by the side walls 5 thereof.

On the head 3 of the pedestal is a table which comprises a horizontal plate 6 provided with a bracket 7 extending upwardly at the front end thereof. The table 6 also carries a vertically ex-

30 tends bracket 8, having a slot 9 therethrough, as best illustrated in Figs. 7 and 8. The table 6 has a slot 10 extending inwardly from its rear edge, which likewise is best illustrated in Figs. 7 and 8.

35 The upper end of the bracket 8 is formed, as illustrated in Fig. 12, to provide a stud 11, with a slot 12 therein, to releasably support the forming member for the forepart of the slip-last upper.

The forming member 13 is illustrated in plan 40 in Fig. 11, and includes a shaped body portion having the general contour of the forepart of a last. This member has in its top wall a T-shaped

45 recess 14, which constitutes a socket so that when the member 13 is mounted on the bracket 8, the socket fits over the stud 11, it being noted that

the stud 11 is dimensioned in respect of the top face of the bracket 8 so as to form a shoulder at either side thereof, whereby the member 13 is releasably supported in a horizontal position, the toe portion of the member extending toward the rear of the machine. The slot 12 in the member 11 and the opening at the left end of the recess 14 (Fig. 11) are provided to accommodate a lead 15 of a heating element 16 that projects into and is seated within a bore 17, that extends

from the toe portion of the body 13 to the opposite end thereof.

It will be understood that the member 13 is formed from a metallic casting so that by heat transfer from the heating element 16, the surface of the member 13 will be heated, and to the greatest extent near the toe portion thereof.

The heel-former member 18 is contoured to the shape of the heel section of a slip-last upper, and is carried on a bar 19, which is slidably mounted at one end in a slot 20 formed in the top face of the bracket 7, and at the opposite end in the slot 9 in the bracket 8. To facilitate the mounting of the bar 19, the slot 20 is open at its upper end and is closed by a plate 21 secured by bolts 22 to the top face of the bracket 7.

Since it is contemplated that the machine may be adapted for widely varying sizes of slip-last uppers, both the members 13 and 18 are designed to be readily replaced by corresponding members, but of different dimensions and contours. Likewise, since the variation in length from toe to heel of the slip-last uppers may be accommodated on the machine, the heel member is made adjustable upon the bar 19, and, for this purpose, the bar 19 may be conveniently provided with a series of spaced openings 23 therethrough so that the member 18 may be locked in different longitudinal positions, with respect to the bar 19, by a key 24 extending through openings 25 in the walls of a slot 26 formed in the bottom wall of the member 18.

After the heel-forming member 18 has been adjusted on the bar 19 at an appropriate longitudinal setting for the selected length of the upper, it may be protracted or retracted toward and from the forepart-forming member 13 by the sliding movement of the bar 19 in its mounting. The bar 19 is actuated to its extended or protracted adjustment by a strong expansion spring 27 mounted upon a rod 28, the front end of which is affixed to a depending lug 29 carried by the lower face of the bar 19. The rod 28 extends forwardly through an opening 30 in the lower part of the bracket 8. The spring 28 bears against the front face of the bracket 8 at one end and against the inner face of the lug 29 at the other end. The spring is designed to exert a strong pressure forcing the bar 19 to its protracted position, and thereby moving the heel-forming member outwardly from the forepart-forming member with substantial force.

The bar 19 is moved in the opposite direction by mechanical connections which include a lever 31 pivoted on a pivot pin 32, which extends between the walls of the slot 10 in the rear end of the base plate or table 6. The upper arm of the lever 31 has a pin and slot connection 33 with a link 34, which has a pivotal connection with a clevis 28a, attached to the rear end of the rod 28.

The lower arm of the lever 31 is actuated by a treadle operated linkage which comprises a foot lever or treadle 35, pivotally supported on a pivot 36, adjacent to the lower end of the pedestal 2. The foot lever operates a pull rod 37, which has an adjustable pivot connection 38 with the foot lever at its lower end and a pivot connection 39 with one arm of a bell crank lever 40. The lever 40 is pivotally supported on a pivot pin 41 mounted in the head section 3 of the pedestal 2. The other arm of the bell crank lever 40 is connected with the lower arm of the lever 31 by a link 42, having a pivot connection 43 with said arm at one end, and with the upper arm of the bell crank lever by a pivot connection 44 at the opposite end.

Since the tendency of the spring 27 is to actuate the linkage by a resilient pull on the upper arm of the lever 31, the parts will normally be in the position illustrated in Fig. 1 in which the heel former 18 is protracted and the foot lever 35 raised. Upon the initial depression of the foot lever 35, the linkage is actuated to move the heel-former member 18 toward the forepart-former member 13 to the position illustrated in Fig. 6. Upon a further depression of the foot treadle 35, the linkage will assume the position illustrated in Fig. 8, which is the position of the operating parts of the machine when it is adjusted to receive the slip-last upper.

15 In order to wipe the toe area of the slip-last upper into place over the toe portion of the forepart-forming member 13 to shape it, a wiping device is provided, which device includes a barrel member 45 which is mounted for swinging movement on trunnions 46 supported on the walls of the slot 10 in the rear end of the plate 6, as best seen in Fig. 10. It will be noted, by reference particularly to Fig. 8, that the rear end of the base plate or table 6 is extended downwardly 20 to form a bracket mounting 47 for the support of the trunnions 46, constituting the pivot for the barrel 45.

25 In the lower portion of the interior of the barrel 45 is an expansion spring 48, which is held in position by a screw plug 49 that threads into a threaded opening in the lower end of the barrel 45, thereby providing means for adjusting the tension of the spring 48. The screw plug 49 may be locked in position by a key 50 after adjustment.

30 Seated for sliding movement in the upper portion of the barrel 45 is a push rod 51. This push rod has a vertical slot 52 therein, which slot is positioned in the lower section of the rod but does not extend through the lower end. The spring 48 abuts against the lower end of the push rod 51 and tends to actuate it upwardly. A roller 53 is supported on a pin 54, extending transversely of the walls of the slot near the lower end thereof, the purpose of which is to constitute an abutment for the lower edge of an arm 55 which extends outwardly from the lever 31. In the normal position, the push rod 51 is fully protracted from the upper end of the barrel by the spring 48 because, in this position, the arm 55 does not exert pressure on the roller 53, and the spring 48 is free to act to raise the push rod.

35 On the initial depression of the foot lever, the lower edge of the arm 55 impinges against the roller 53 and forces the push rod 51 downwardly 55 in opposition to the spring 48. This is the position of the parts most clearly illustrated in Fig. 7.

40 On further depression of the foot treadle, the end of the arm 55 contacts with a cam face 56 formed on the upper wall of a lug 57 formed on the wall of the barrel 45 adjacent to the base of the slot 52. This action is best illustrated in Fig. 8 from which it will be observed that, upon full depression of the foot lever, the end of the arm 55, by cam action with the cam face 56, swings 60 the upper portion of the barrel 45 to the right, in opposition to the tendency of a contractual spring 58 attached at one end at 59 to the barrel 45 near its upper end, and to the bracket 8 at 60 the other end of said spring.

65 Obviously, when pressure is partially released on the foot treadle, the parts will first return to the adjustment shown in Fig. 7, when the cam action between the end of the arm 55 and the cam face 56 is released. The barrel will thereupon 70 swing to a vertical position but with the push rod 75 swing to a vertical position but with the push rod

51 depressed within the barrel, as illustrated in Fig. 7.

Further release of pressure on the foot treadle permits the spring 48 to move the push rod 51 upwardly to the position shown in Figs. 1 and 9.

The upper end of the push rod 51 has a head 61, integrally formed therewith, having its rear face curved to receive a curved wiping plate 62, the inner surface of which plate is formed so that it will lie closely adjacent to the extreme toe portion of the forepart-forming member 13. As the plunger rod moves upwardly, the plate 62 will contact the toe portion of the upper and smooth it over the toe area of the forming member 13. As the plunger rod is pressed upwardly with substantial pressure, the upper edge thereof presses against the marginal seam between the inverted platform cover and the upper, thereby flattening out the sock lining at the toe to rework the pucker, and also raises the extended margin beyond the seam, as illustrated in Figs. 13 and 14, thus forming the toe portion of the upper to a close fit with the toe portion of the forepart-forming element 13, as well as setting the box toe insert in finished contour relation with the inner surface of the upper.

From the foregoing, it will be understood that the machine operates in the following manner.

A slip-last upper is assembled by stitching the upper *a* and sock lining *b* to the outturned margin of the inverted platform cover *c*, in the relationship of parts shown in Fig. 13, with a box toe insert *d* in the toe portion of the upper between the inner surface thereof and the lining *e*. An upper, thus constructed, is then fitted over the forming elements 13 and 18 when the foot lever is fully depressed. This step is best shown in Fig. 8, from which it will be noted that the positioning of the upper in the machine may be readily accomplished, because the heel-forming element 18 is retracted toward the forepart-forming element 13.

It is to be understood that it is contemplated that the box toe insert *d* is of a fabric material impregnated with a thermo-plastic material which, when heated, will set to form.

Before the parts have been set, and when assembled, as first described, the sock lining around the toe section tends to pucker because of the inability, without further forming, to force the box toe insert into the space between the sock lining and the extreme toe portion of the upper.

After the upper has been mounted, as illustrated in Fig. 8, partial pressure on the foot lever is released, and the barrel 45 swings to a vertical position, as illustrated in Fig. 7. In this position, the wiping and forming plate 62 is below the plane of the forepart-forming member 13, but in vertical alignment therewith. This position is illustrated in Fig. 7.

Upon further release of pressure on the foot treadle, the spring 27 forces the heel-former element 18 away from the forepart-forming member 13 and thereby stretches the upper lengthwise, causing it to form around the forepart-former member 13. It will be understood that, during this step, the thermoplastic box toe insert is heated sufficiently to form and set in place in the toe of the upper, and, as the wiping plate is raised, it wipes the toe area of the upper and, in effect, provides a pressure member exerting pressure on the outer surface of the toe area of the upper and thereby forcing the box toe insert into position in the toe of the upper. This action also removes the pucker in the sock lining adjacent to

the seam and in the area of the toe portion of the upper; and, at the same time, tends to raise the margin of the elements of the slip-last upper beyond the seam. The position of the parts, as a result of this operation, is best illustrated in Figs. 13 and 14. The ultimate result is the production of a formed slip-last upper in which the elements of the upper at the toe section, as illustrated in Figs. 9, 13 and 14, are properly formed to provide a smooth finish, true to size and contour.

The product of the operation of the machine has been illustrated in enlarged form in Figs. 13 and 14, from which it will be observed that the sock lining *b* is entirely free from pucker at the seam; and that the box toe insert *d* and the lining *e* are forced into place around the inner margin of the seam, and that the outer margin, which comprises the sock lining *b*, the upper *a*, and the edge of the outturned platform cover *c*, is in a true vertical plane. This provides a smooth shoe margin when the platform cover *c* is turned over the marginal edge of the platform *f* in the manner illustrated in Fig. 14.

The machine, therefore, provides a simple construction which may be rapidly and economically operated for the satisfactory production of slip-last uppers, which are accurate to dimensions and which may be finished into slip-last shoes having the required smooth appearance, free from wrinkles or pockers in any part of the margin of the shoe.

It should be mentioned that the invention contemplates the setting of a heel counter, if desired, by providing a heating element therein, similar to that illustrated for the forepart-former element. It should be understood, therefore, that the invention may be modified and extended to include equivalent structure within the scope of the claims.

40. What is claimed is:

1. In a machine for forming closed slip-last uppers having a box toe insert formed and adhered by the application of heat, comprising a base, a forepart-forming member insertable in the forepart of the upper and conforming to the inner contour thereof and having a longitudinal recess extending to the toe end of said member, a heating element removably insertable in said recess in said forming member, means for exerting a stretching force on said upper when mounted on said forming member to conform the upper thereto and to set said box toe insert, a wiping device movable across the toe section of the upper adjacent to the toe portion of said forepart-forming member, and mechanical means for moving said wiping device vertically in respect of forepart-forming member.

2. In a machine for forming closed slip-last uppers having a box toe insert formed and adhered by the application of heat, comprising a base, a forepart-forming member insertable in the forepart of the upper and conforming to the inner contour thereof, means for exerting a stretching force on said upper when mounted on said forming member to conform the upper thereto and to set said box toe insert, a wiping plate movable vertically with respect to the toe portion of said forepart-forming member for wiping said toe section of the upper over said forming member, and mechanical means for moving said wiping plate vertically in respect of said forepart-forming member while said member remains stationary.

3. In a machine of the class described, a base plate, supports carried by said base plate and

relatively movable with respect to each other, a forepart-forming member and a heel-forming member carried by said supports respectively, a resilient means for protracting said supports from each other, manipulative means to impart relative movement to said supports to retract said forming members toward each other, and a wiping device comprising a plunger rod, a wiping plate mounted on said rod movable into and from a position adjacent to the toe of said forepart-forming member, and manipulative means for moving said plunger rod to bring said wiper plate adjacent to the toe section of said forepart-forming member.

4. In a machine of the class described, a base plate, supports carried by said base plate and relatively movable with respect to each other, a forepart-forming member and a heel-forming member carried by said supports respectively, means for protracting said supports from each other, means to impart relative movement to said supports to retract said forming members toward each other, a wiping device comprising a plunger rod, a wiping plate mounted on said rod movable into and from a position adjacent to the toe of said forepart-forming member, means for operating said plunger rod in coordination with said means imparting relative movements to said supports.

5. In a machine of the class described, a base plate, supports carried by said base plate and relatively movable with respect to each other, a forepart-forming member and a heel-forming member carried by said supports respectively, resilient means for protracting said supports from each other, manipulative means to impart relative movement to said supports to retract said forming members toward each other, in combination with a wiping device comprising a plunger rod, a wiping plate mounted on said rod for movement into and from a position adjacent to the toe of said forepart-forming member, manipulative means for moving said plunger rod to bring said wiper plate adjacent to the toe section of said forepart-forming member, and means for

8
swinging said support out of the vertical plane of the toe section of said forepart-forming member when said supports are in retracted position.

6. In a machine of the class described, a base plate, supports carried by said base plate and relatively movable with respect to each other, a forepart-forming member and a heel-forming member carried by said supports respectively, means for protracting said supports from each other, means for moving said supports to retract said forming members toward each other, in combination with a wiping device comprising a plunger rod, a plunger plate mounted on said rod to and from a position adjacent to the toe of said forepart-forming member, a support for said plunger rod, and means moving said support into alignment with the toe section of said forepart-forming member when said supports are protracted, and means moving said support away from the plane of alignment with said forming member when said supports are moved to retracted position.

7. In a machine of the class described, a support for a shoe upper, a wiping plate curved to conform to the toe section of said support, a pivoted carrier for said wiping plate, mechanical means for imparting to said carrier arcuate and vertical movements whereby said carrier is moved into the vertical plane of the upper support and moved vertically in respect thereof to contact the toe end of said upper support, and moved in the opposite direction in respect of said upper support and moved angularly away from the vertical plane of the toe portion of said support.
